UNITED STATES PATENT OFFICE.

WILLIAM L. MCKEAN, OF MARTINS FERRY, OHIO.

MACHINE FOR CLEANING AND POLISHING TIN SHEETS.

1,155,671.

Specification of Letters Patent.

Patented Oct. 5, 1915.

Application filed March 18, 1915. Serial No. 15,309.

To all whom it may concern:

Be it known that I, WILLIAM L. MCKEAN, residing at Martins Ferry, in the county of Belmont and State of Ohio, a citizen of the 5 United States, have invented or discovered certain new and useful Improvements in Machines for Cleaning and Polishing Tin Sheets, of which improvements the following is a specification.

10 In the accompanying drawings forming a part of this specification, Figure 1 is a view partly in section and partly in elevation of a cleaning and polishing machine embodying my improvements; Fig. 2 is a transverse 15 section on a plane indicated by the line II—II Fig. 1; Fig. 3 is a sectional view on an enlarged scale of portions of rolls illustrating the irregular surfaces produced in the operation of the machine; Figs. 4 and 20 5 are transverse sections of the rolls, Fig. 4 showing ridges or projections on the rolls in contact with the sheet and Fig. 5 showing bran held in depressed portions of the roll in contact with the sheet.

25 In the manufacture of tin plate, the pickled sheets are passed down through a box containing a suitable flux into the molten tin, and are then moved upwardly out of the tin and through a quantity of palm oil 30 or other suitable material adapted to protect the tin from oxidation while solidifying. While the sheet is passing vertically through the oil the excess of tin will drain off, being maintained in a molten condition 35 by the palm oil. But as the tin adherent to the sheet is not uniformly distributed and the thickness of the coating is greater than desired or necessary, the sheet is passed between a series of accurately turned rolls, ar- 40 ranged in tandem vertically in the palm oil so that the tin will be maintained in molten condition while the sheets are in the bite of the rolls. These rolls operate to squeeze off all surplus tin and insure an even distribu- 45 tion of the thin coat adherent to the sheets.

As before stated, the palm oil serves not only to keep the tin molten while the sheets are passed between the rolls, but the film of oil on the tinned or coated surfaces protects 50 the latter from oxidation to which the tin is susceptible while in a molten or highly heated condition. While the use of palm oil or any equivalent material is necessary during the coating operation its presence on the 55 surfaces, renders the sheets useless for practically all purposes and must therefore be

removed. It is necessary not only to remove all traces of the oil from the surfaces of the sheets but such surfaces must be buffed or polished for the reason that the coating is 60 generally only one ten thousandth (1/10,000) of an inch in thickness and being laid on the dark steel surfaces will appear dull. On account of the thinness of the coating the 65 cleaning and buffing or polishing of the sheets must be effected by means of a material not liable to injure the thin tin coating. As the oil can be most easily removed before it has solidified and as the tin coating must be completely solidified before being sub- 70 jected to the buffing operation, the cleaning and polishing must be quickly effected while the sheets are at a temperature at which the above conditions occur simultaneously. Formerly the cleaning and polishing were ef- 75 fected by passing the sheets through a mass of saw dust, middling, bran or other suitable material. This crude method has been supplanted by feeding bran, etc., together with the sheet between pairs of rolls 80 formed of disks of fibrous material, one roll of each pair rotating at a higher speed than the other roll. In some forms of machines the rolls are arranged in a box filled with bran, sawdust or other material, and in an- 85 other the rolls were horizontally mounted in a box and the latter filled to a level slightly above a plane tangential to the lower rolls. In both forms of machines the rolls of each pair are spaced a slight distance apart so as 90 to insure a substantial layer of bran passing into the bite of the rolls on each side of the sheets, the movements of the sheets being effected by means other than the rolls or by the rolls operating through the layers of 95 bran, the rate of movement of the sheets being the average of the peripheral speeds of the rolls. In both forms of machines the particles of bran or other material were only slightly compacted together and the oil 100 was drawn from the surfaces of the sheets principally by capillary attraction into the minute spaces between the particles of cleaning material or absorbed by the particles themselves. The buffing was due solely 105 to the movement of the particles along the surfaces the pressure of the particles on the surfaces being light. A decided improvement in the operation of these machines was brought about by adjusting the rolls so that 110 their peripheries would bear firmly one against the other and consequently with

greater pressure on the layers of bran and the sheets. With the rolls so adjusted the particles of bran are compacted closely together and against the surfaces of the sheets 5 when in the bite of the rolls. As the particles of bran are yielding and resilient they form a dense layer when compacted, but when freed from the bite of the rolls the compacted layers open up and with sponge-like action suck the oil from the surfaces. 10 And further while so compacted the bran operates more efficiently to buff or polish the surfaces.

Although the rolls when new have regular uniform surfaces, the latter do not wear uniformly and ridges or projections α are soon formed as shown in Fig. 5, and it is the usual practice to rotate the rolls in contact with one another in bran without sheets 15 passing between them, until soft surfaces suitable for buffing are formed. When the rolls are thus worn the tops of the projections or ridges force the greater part of the bran aside and some directly into contact 20 with the sheets as shown in Fig. 3, and the bran will pass into the bite of the rolls at the depressed spots or grooves as shown in Fig. 4, so that in one pair of rolls only portions of the surface will be cleaned and polished. 25 Hence four or more pairs of rolls are employed so as to insure a complete cleaning and polishing.

It will be readily understood that particles of bran more or less soaked with oil should 30 not be used in the above operations, and it has been found that where the bran is compacted between the surfaces of the rolls and the sheets portions thereof in the form of streaks or spots will adhere to the fibrous 35 surfaces of the rolls and will be carried into contact with the surface of another sheet and will make an oily spot and being more or less completely charged with oil will not operate efficiently. And further where the 40 rolls rotate in a body of bran, particles charged with oil may be carried around by the rolls although not tightly adherent thereto, and forced in between the rolls and sheet a second time.

50 The invention described herein which has for its object a construction and combination of parts or elements whereby bran or other material is prevented from being brought a second time in contact with the 55 surface of the sheets, is hereinafter more fully described and claimed.

In the practice of the invention a series of pairs of rolls 1, 2, 3, 4, etc., have their journals mounted in blocks 5 and 6 arranged in 60 windows 7 in the sides 8 of the machine. The bearing blocks 6 of the lower rolls rest on the bottoms of the windows but the bearing blocks 5 are movable in the windows by the screws 9 to regulate the pressure of the 65 rolls on the sheets and bran passing between

them. As hereinbefore stated the bodies of these rolls are yielding consisting of disks of close compacted fibers, and it is preferred that the rolls should be so adjusted that the surfaces in contact one with the other or 70 with the sheets will be substantially flattened, as shown in Figs. 1, 3 and 4.

In cleaning the sheets the latter are placed on the table 10 at the front end of the machine and slid into the bite of the first pair 75 of rolls. While moving into the bite of the rolls the sheets pass through a pile of bran which has collected in a pocket formed by the rolls 1 and block 11 interposed between the lower roll and a cross bar 12 secured 80 to the front ends of the sides of the machine. The bran is fed in a thin stream through the spout 13 onto the revolving distributing screen 14 which throws it against the upper roll from which it drops into the 85 pocket. In order to maintain a sufficient quantity of bran intermediate of adjacent pairs of rolls, the space between the lower rolls of each pair is closed by a member 15 which is preferably formed of an angle as 90 shown in Fig. 1. It is preferred that these members which bear against adjacent lower rolls, should be so mounted as to have a rocking or swinging movement as they are subjected to the uneven surfaces of the rolls. 95 When angle bars are employed the lower ends 16 of rods 17 are turned inwardly to serve as pivotal supports for the bars. The upper ends of the rods pass through lugs 18 and are threaded for the reception of nuts, 100 whereby the positions of the angle bars may be adjusted. In the operation of the machine it is preferred that the members 15 should be so adjustable as to exert a slightly deforming pressure on the rolls or to leave 105 some space according to the condition and character of the cleaning material so that any crust of bran adhering to the surfaces of the rolls will be broken up when the surface of the roll is deformed or will be rubbed off by the bran and will be carried along it until the particles can drop. If any particles are not removed by the first member encountered they will be scraped off by the next member, which will then be crowded against 115 the upward moving face of the roll so no particle can pass a second time into contact with a sheet. A substantial interval occurs between the movements of succeeding sheets 120 into the rolls and hence the latter which rotate at considerable speed will bear on one another or rather on such layer of bran as may be drawn in between the rolls. As the rolls are so adjusted as to bear with a surface deforming pressure one on the other any 125 crust of bran formed on the upper roll will be broken up by such deformation and the particles forming such crust will be carried around by the lower roll and discharged. The scraping member 15^a bearing against 130

the upwardly moving surface of the front lower roll, is adjustably supported by the cross-bar 12. The ends of the pockets for the bran or other material formed by adjacent rolls and the part or member 15, may 5 be closed by plates 19 suitably supported by the sides of the frame, as shown in Fig. 2.

I claim herein as my invention:

1. In a machine for cleaning and polishing tin sheets, the combination of a plurality of spaced pairs of rolls, and means arranged between adjacent lower rolls for supporting cleaning material in the line of movement of the sheets through the machine.
2. In a machine for cleaning and polishing tin sheets, the combination of a plurality of pairs of rolls having yielding surfaces, and means for applying deforming

pressure to the surfaces of the lower rolls 20 at points below the axes of the rolls.

3. In a machine for cleaning and polishing tin plates, bars arranged intermediate adjacent lower rolls, and means for adjusting the positions of the bars relative to the 25 rolls.

4. In a machine for cleaning and polishing tin sheets, the combination of a plurality of pairs of rolls, angle bars arranged intermediate adjacent lower rolls, and means 30 for raising and lowering said angle bars.

In testimony whereof, I have hereunto set my hand.

WILLIAM L. McKEAN.
